(57) **CLAIM**

The ornamental design for a combination frame for an electric bicycle and housing for a motor and batteries, as shown and described.

DESCRIPTION

FIG. 1 is a front perspective view of a combination frame for an electric bicycle and housing for a motor and batteries, showing my new design;

FIG. 2 is a right side elevation view thereof;

FIG. 3 is a left side elevation view thereof;

FIG. 4 is a front elevation view thereof;

FIG. 5 is a top plan view thereof;

FIG. 6 is a rear elevation view thereof; and,

FIG. 7 is a bottom plan view thereof.

The broken line showing of the bicycle components is provided for the purpose of illustrating environmental structure and do not for part of the claimed design.
